UNITED STATES PATENT OFFICE.

FREDERICK J. KALDENBERG, OF NEW YORK, N. Y.

DESIGN FOR AN UMBRELLA-HANDLE.

SPECIFICATION forming part of Design No. 11,734, dated April 13, 1880.

Application filed February 26, 1880. Term of patent 3½ years.

To all whom it may concern:

Be it known that I, FREDERICK J. KALDENBERG, a citizen of the United States, residing at New York, in the county and State of New York, have invented and produced a new and original Design for an Umbrella or Parasol Handle, of which the following is a specification, reference being had to the accompanying drawing, forming part thereof.

10 The object of my invention is to produce a novel and ornamental design for the upper part of an umbrella or parasol handle; and the design consists, first, in giving to the handle the configuration of an anchor, and, second, in giving to it the configuration of an anchor with the cable twined around it.

15 My new design is fully illustrated in a side view in the accompanying drawing, in which *a* is the circular or lower part of the handle; *b*, the shank of the anchor; *c*, the stock; *d*, the arms, and *e e* the flukes. On the ends of the stock are caps *f f*, which may be made of gilded or silvered material to add greater

beauty to the design. *g* represents the cable, which is twined around the anchor.

25 What I claim as my invention, and desire to secure by Letters Patent, is—

1. The design for an umbrella or parasol handle, consisting of the representation of an anchor, substantially as described, and shown 30 in the accompanying drawing.

2. The design for an umbrella or parasol handle, consisting of the representation of an anchor with the cable twined around it, substantially as described, and shown in the accompanying drawing. 35

3. The design for an umbrella or parasol handle, consisting of the representation of an anchor with caps on the ends of the stock, substantially as described, and shown in the 40 accompanying drawing.

FREDERICK J. KALDENBERG.
